STOCKING

William M. Langer, Berlin, N. J.

Application June 19, 1953, Serial No. 25,577

Term of patent 14 years

(Cl. D47—7)

To all whom it may concern:

Be it known that I, William M. Langer, a citizen of the United States, residing at Berlin, in the State of New Jersey, have invented a new, original, and ornamental Design for a Stocking, of which the following is a specification, reference being had to the accompanying drawing, forming a part hereof.

In the drawing:

Fig. 1 is a side elevational view of a stocking embodying my new design; and

Fig. 2 is an enlarged, fragmentary, rear elevational view thereof.

I claim:

The ornamental design for a stocking, as shown.

WILLIAM M. LANGER.
